PARACHUTE HARNESS

Frank G. Manson, Dayton, Ohio

Application August 6, 1940, Serial No. 351,636

11 Claims. (Cl. 244—151)

(Granted under the act of March 3, 1883, as
amended April 30, 1923; 370 O. G. 757)

The invention described herein may be manufactured and used by or for the Government for governmental purposes, without the payment to me of any royalty thereon.

The present invention relates to improvements in parachute harness for supporting the body of the wearer during a parachute descent.

The object in general of the invention is to provide a new and improved parachute harness of simplified construction which has great strength, which is convenient to adjust, and which is capable of quick release and disengagement from the body of the wearer.

A particular object of the present construction is to provide a harness wherein a pair of lift webs are adapted to extend in substantially parallel relation down the back of the wearer and terminate in leg straps, so that most of the weight of the wearer's body is carried directly by the continuous material of the lift webs, thereby avoiding large stresses in stitched connections.

Other objects and advantages reside in the construction of parts and the combination thereof as will become more apparent from the following description.

In the drawings, wherein for the purpose of illustration there is shown only a preferred embodiment of the invention:

Figure 1 is a view of the harness with the parts extended; and

Figure 2 is a view of the harness with the parts connected together in the positions they would assume on a wearer.

In the present harness, designed for use with the back type of parachute pack, there are provided a pair of lift webs 1 and 2 equipped with rings 3 and 4 for securing the shroud lines from the parachute canopy. The lift webs 1 and 2 are adapted to be disposed in substantially parallel relation down the back of the wearer, and terminate in what may be termed leg straps 5 and 6 carrying at their ends the connector parts 7 and 8. The leg straps 5 and 6 are provided with length-adjusting buckles 9 and 10 in such a manner that each leg strap passes once through the adjusting buckle, then around the eye in the connector part and back to the adjusting buckle, where it is secured by being doubled around one of the bars thereof and stitched back on itself in the manner shown in Figure 2.

A seat strap 15 is provided with enlarged loops, as shown at 16 and 17, so as to be longitudinally adjustable on the lift webs 1 and 2. Preferably,

the loops 16 and 17 are intended to be stitched to the lift webs in the proper position to best fit a particular individual, but this stitching may be light hand stitching, as it is not subjected to appreciable stress.

5 A back strap 18 formed of wide webbing material is attached in transverse relation to the lift webs 1 and 2 by stitching or other equivalent means. The length of the back strap 18 is such that the end portions 19 and 20 partially encircle the waist of the wearer. Short loops of webbing 21 and 22, or other strong material, are attached to the end portions 19 and 20, preferably by stitching in the regions indicated at 23. 10 Rings 24 and 25 are carried by the loops 21 and 22 and are thus definitely positioned by means of the stitching in the parts 23.

A pair of crossed shoulder straps are shown at 30 and 31 passing diagonally downwardly and 15 through the rings 25 and 24, respectively. The ends of the straps 30 and 31 are secured in overlapping relation so as to anchor the same by means of the length-adjusting buckle 32, this buckle being preferably positioned at one side of 20 the wearer so that a smooth strip of the belt 30 will lie against the wearer's back underneath the back strap 18. Shoulder straps 30 and 31 pass through adjusting buckles 33 and 34, respectively, 25 on the lift webs 1 and 2, the function of the last-named buckles being to adjustably fix and 30 determine the point of attachment of the back straps to their respective lift webs. Connecting parts 35 and 36 are attached to the ends of the back straps 30 and 31 in a well-known manner 35 and for a purpose presently to be described.

Thus it is seen that the back strap 30 begins at one end with the connecting part 35, passes through the adjusting buckle 33 on the lift web 1 and then proceeds diagonally across the back 40 of the wearer to the ring 25, where it doubles back upon itself and lies against the back strap 18 until it reaches the buckle 32, where its other end is anchored in proper adjustment. Similarly, the shoulder strap 31 begins at one end at the connecting part 36, proceeds through the buckle 34 on the lift web 2 and then passes diagonally 45 across the back of the wearer to the ring 24 and thence into the adjusting buckle 32 in the opposite direction from the strap 30. Both of the straps 30 and 31 are frictionally held in proper adjustment in the adjusting buckle 32, there being no positive attachment to this buckle. In

order to provide for adjustment of the shoulder straps, both of the straps 30 and 31 are free for 50 longitudinal movement with respect to the back

strap 18, so that their lengths may be altered by sliding them through the rings 24 and 25, and also through the adjusters 33 and 34, if necessary.

It is thus seen from Figure 1 that the lower extremities of the lift webs 1 and 2, which are in reality the ends of the leg straps 5 and 6 carrying the connecting parts 7 and 8, may be called free ends. Similarly, the upper extremities of the shoulder straps carrying the connecting parts 35 and 36 may also be called free ends. A connecting device 40 is employed for securing together these four free ends in the manner shown in Figure 2 when the harness is applied to the body of a person, the connecting parts 7, 8, 35, and 36 being engaged with the connector 40 by means of snap-acting latches. The connector 40 is of a type having a release button 41 capable of simultaneously releasing all of the connector parts 7, 8, 35, and 36. It may be found desirable, however, to permanently attach the connector 40 to one of the connecting parts, such as 35, so that the connector 40 will always remain with the harness and be carried by one of the straps. The specific construction of this connector forms no part of the present invention, and any equivalent connector may be used.

The manner in which the harness fits the wearer is apparent in Figure 2. The lift webs 1 and 2, when they are supported by the shroud lines from the canopy of the parachute attached to the rings 3 and 4, will be disposed in substantially parallel relation down the back of the wearer. The lower parts of the lift webs 1 and 2 form leg straps 5 and 6 supporting a greater part of the wearer's weight. The leg straps 5 and 6 are disposed in front of the wearer and there engaged by the loops 21 and 22 in the ends of the back strap 18, thereafter upwardly converging toward the connector 40. The shoulder straps 30 and 31 cross behind the wearer's back and pass over the wearer's shoulders for engagement with the connector 40, to resist the downward pull of the leg straps.

Thus it is seen that substantially the entire weight of the wearer's body is borne by the material of the lift webs alone without involving the strength of any stitched portions or connections with other straps. The weight is supported by means of a direct pull in tension on each of the lift webs in substantially a straight line from the wearer's thighs to the connection with the shroud lines of the parachute. This construction makes for great strength, as well as simplicity of design, ease of adjustment, and the possibility of a quick release from the harness after the descent.

A considerable range of adjustment for different sizes of individuals is possible through changing only the adjusters 9 and 10, but if greater adjustment is desired, the length of the shoulder straps may be varied by means of the buckle 32.

Release of the harness from the body of the wearer may be quickly effected by operation of the knob 41 on the connector 40, which allows the previously mentioned free ends to separate. Tension on the leg straps will easily draw the ends of the latter free of the large loops 21 and 22, whereupon the wearer is immediately completely disengaged from the harness.

While I have shown and described but a single embodiment of my invention, it is to be understood that it is capable of many modifications. Changes, therefore, in the construction and arrangement may be made which do not depart from

the spirit and scope of the invention as described in the appended claims.

I claim:

- 5 1. A parachute harness comprising a pair of substantially parallel lift webs extending the full length of the wearer's back, each of said lift webs terminating in a leg strap having a free end disposed in front of the wearer; a webbing strap attached transversely to said lift webs so as to be disposed horizontally across the wearer's back, said webbing strap having a leg-strap-engaging loop at each end thereof; an adjustable strap secured to said webbing strap and having reaches extending diagonally across the wearer's back and from approximately said loops respectively to an opposite shoulder of the wearer, said reaches terminating in free ends disposed in front of the wearer; and quick-release fastening means for securing together all of said free ends.
- 10 2. A parachute harness comprising a pair of substantially parallel lift webs extending the full length of the wearer's back and terminating in adjustable leg straps having free ends for disposition in front of the wearer, a strap having a portion attached transversely across said lift webs and having leg-strap-engaging loops, a shoulder strap extending approximately from each of said loops and across an opposite shoulder of the wearer, said shoulder straps passing through guides on said lift webs at approximately shoulder height and terminating in free ends, and quick-release fastening means for securing together all of said free ends.
- 15 3. In a parachute harness, a pair of lift webs adapted to extend in parallel relation down the back of the wearer, each of said lift webs terminating in a free end; a transverse strap attached to said lift webs in a position to embrace the back of the wearer; a loop at each lateral extremity of said transverse strap adapted to receive one of said lift webs near the free end thereof; diagonal straps extending from the regions of said loops across the opposite shoulders of the wearer and terminating in free ends; and quick-release fastening means for securing together all of said free ends in front of the wearer.
- 20 4. A parachute harness comprising a pair of substantially parallel lift webs, an extremity of each of said lift webs constituting a leg strap terminating in a free end; a strap secured to said parallel lift webs in transverse relation thereto and carrying leg-strap-engaging loops on opposite sides thereof; shoulder straps anchored to said loop-carrying strap and terminating in free ends; and quick-release fastening means for securing together all of said free ends.
- 25 5. In a parachute harness, a pair of lift webs adapted to extend down the wearer's back in substantially parallel relation and terminating in leg straps, each having a free end; loops adapted to engage said leg straps in front of the wearer; diagonal straps extending from adjacent said loops across the back of the wearer and over opposite shoulders, and terminating in free ends; and quick-release fastening means for securing together all of said free ends in front of the wearer.
- 30 6. A parachute harness comprising a pair of lift webs, the lower extremities of which constitute adjustable leg straps; means loosely interconnecting said lift webs to form an adjustable seat portion; shoulder straps attached to said lift webs; and releasable means for attaching said leg straps to said shoulder straps.
- 35 7. A parachute harness comprising a pair of

lift webs, the lower extremities of which constitute leg straps; a back strap secured transversely to said supporting webs, said back strap having at each end thereof a loop for slidably receiving a leg strap therethrough; a seat strap spanning said lift webs and associated therewith so as to be slidably adjustable therealong; shoulder straps attached to said lift webs; and means for attaching the ends of said shoulder straps to the ends of said leg straps.

8. A parachute harness comprising a pair of lift webs, the lower extremities of which constitute adjustable leg straps; a seat strap spacing said supporting webs; a back strap bridging said supporting webs and adapted to loosely engage intermediate portions of said leg straps; and a pair of mutually engageable chest straps, each attached to one of said supporting webs.

9. A parachute harness comprising a pair of

lift webs terminating in leg straps, and a strap attached transversely to said lift webs and having means for loosely engaging intermediate portions of said leg straps, said transverse strap having attached thereto crossing shoulder straps having engagement with said lift webs above the points of said transverse attachment.

10. A parachute harness comprising a pair of lift webs, the lower extremities of which constitute adjustable leg straps, means spacing and interconnecting said lift webs to form a seat portion; shoulder straps attached to said lift webs; and means for attaching said leg straps to said shoulder straps.

11. In a parachute harness, a pair of lift webs and a seat strap spacing and loosely connecting said lift webs intermediate their ends so as to be adjustable therealong.
